Primary Examiner — Lauren D McVey*Assistant Examiner* — Elisa M Pujals(74) *Attorney, Agent, or Firm* — Banner & Witcoff, Ltd.(57) **CLAIM**

The ornamental design for a gaming machine as shown and described.

DESCRIPTION

FIG. 1 is a front perspective view of a gaming machine showing my new design;

FIG. 2 is a front view thereof;

FIG. 3 is a left side view thereof; and,

FIG. 4 is a right side view thereof.

The uneven-length broken lines immediately adjacent to the shaded areas depict the bounds of the claimed design. The even-length broken lines depict environment which forms no part of the claimed design.

1 Claim, 4 Drawing Sheets(56)
